COIN AND TOKEN SEPARATOR

Walter A. Tratsch and Bernhard C. Grunig,
Chicago, Ill.

Application May 4, 1936, Serial No. 77,670

5 Claims. (Cl 194—102)

This invention relates to coin and token separators.

It is an object of this invention to provide an improved coin and token separator which is relatively simple and inexpensive in construction and efficient in use.

Another object of the present invention is to provide a novel and improved coin and token separator which is especially adapted for use in conjunction with token dispensing devices, and which is so constructed that it will permit the amusement apparatus with which the separator is associated to be operated either by a token or by a coin of the proper diameter, denomination, etc., but will discharge the tokens used to operate the device into a storage magazine provided for the reception of the same in the cabinet of the said combination amusement and token dispensing device; and which will discharge the coins which are used to operate the device into a separate receptacle provided therefor in the cabinet of the combination amusement and token dispensing device in conjunction with which the present separator is used, thereby assuring that the combination amusement and token vending device with which the present separator is used will vend only tokens redeemable in merchandise, prizes or the like, and not coins.

A further object of the present invention is to provide a novel and improved coin and token separator which is so constructed that it will permit the amusement apparatus, with which the separator is associated, to be operated either by a token or by a coin of proper diameter, denomination, etc., and will normally discharge the tokens used to operate the device into a storage magazine provided for the reception of the same in the cabinet of the said amusement device; and which will normally discharge the coins which are used to operate the device into a separate receptacle provided in the cabinet of the said amusement device; thereby assuring that tokens be stored in one compartment and that coins be stored in a separate and different compartment, the said token separator being constructed in such a manner that by the insertion of a peg into the frame of the said token separator, a part of the latter will become inoperative and thereby convert the device into a conventional type coin chute wherein all tokens, coins, and the like, used to operate the amusement device are discharged into one compartment.

Other objects will appear hereinafter.

55 The invention consists in the novel combina-

tion and arrangement of parts to be hereinafter described and claimed.

The invention will be best understood by reference to the accompanying drawings showing the preferred form of construction, and in which:

Fig. 1 is a fragmentary top plan view of a combination amusement and token vending device showing a preferred form of the present coin and token separator associated therewith;

Fig. 2 is a central vertical sectional view of the new coin and token separator, on line 2—2 in Fig. 2, showing the parts in their initial or coin-receiving position;

Fig. 3 is a top plan view, on line 3—3 in Fig. 2;

Fig. 4 is a fragmentary bottom plan view, on line 4—4 in Fig. 2;

Fig. 5 is a fragmentary sectional plan view taken on line 5—5 in Fig. 2, showing the movable parts therein disposed in normal position;

Fig. 6 is similar to Fig. 5, but showing a coin associated with the movable parts and the latter disposed in an intermediate position;

Fig. 7 is similar to Fig. 5, but showing the movable parts disposed in full stroke position;

Fig. 8 is similar to Fig. 5, showing a movable part therein disposed in normal position, but showing a part of the coin and token separator in an inoperative position with respect to the said movable part;

Fig. 9 is a transverse sectional view on line 9—9 in Fig. 3;

Fig. 10 is a transverse sectional view similar to that shown in Fig. 9, but showing a part of the coin and token separator in an inoperative position as seen in the plan view of Fig. 8; and

Fig. 11 is a fragmentary elevational view taken along line 11—11 in Fig. 3.

A preferred form of the present coin and token separator is shown in the drawings, is therein generally indicated at 10, and is shown in its preferred use, namely, as used in conjunction with a combination amusement and token vending device, which is generally indicated at 11 (Fig. 1), this combination amusement and token vending device 11 including a token storage magazine or receptacle 12 provided in the cabinet of the same (Fig. 2) for the reception of tokens which may be dispensed from the device (by means not shown) by the successful operation of the same, and which tokens may either be used for operating the device, that is, for releasing the coin control, or for purchasing merchandise, as the proprietor of the device and the player may desire.

The new coin and token separator 10 com-

55

prises a guide structure which is generally indicated at 13, and a coin slide 14, the guide structure 13 being provided with a face plate or mounting plate 15, by means of which the present coin and token separator may be attached to a wall 16 of the cabinet of the combination amusement and token vending device 11 (Fig. 2); and the separator 10 is also provided with the usual dogs and other fraud-prevention devices, generally indicated at 17, for preventing the use of spurious or fraudulent coins or tokens, such devices being preferably those described in Patents Nos. 1,908,380, 1,908,752 and 2,026,921.

It is also to be noted that the present coin and token separator is shown as being associated with a coin chute of the type described in the above-mentioned Patents Nos. 1,908,380, 1,908,752 and 2,026,921, and hence only so much of the construction of that coin chute will be described herein as is necessary for an understanding of the present invention.

Provided in the guide structure 13 is a depressed ledge 42 onto which coins or tokens are discharged from the coin aperture 19 of the coin slide 14, and in addition to the usual devices 17 for preventing the use of spurious or fraudulent coins or tokens, the present coin and token separator is preferably provided with a sight opening or pocket 18 into which the coins or tokens are discharged from the depressed ledge 42 (Fig. 2), this sight opening 18 being formed, in part, as a recess or opening which is provided in a wall 20 of the guide structure 13, the construction of this sight opening or pocket 18 being more fully described and claimed in the applicant's co-pending application Serial No. 11,103, filed March 14, 1935.

When a coin or token is disposed in the sight opening or pocket 18, it rests upon the bottom wall 21 of a guide structure 22 which is arranged below the guide structure 13. Carried by this guide structure 22 is an auxiliary slide 23, and this guide structure 22 is supported by and is suspended from the guide structure 13. Provided in the lower or auxiliary slide 23 is a coin or token-receiving aperture 38 having an opening 52 formed at one edge 27 of the slide 23.

Formed in the bottom wall 21 of the guide structure 22 (Figs. 2, 4, 5, 6, 7, 8, 9 and 10) is a substantially oval-shaped token discharge aperture 24, and likewise formed in the bottom wall 21 of the guide structure 22 is a coin discharge aperture 25, these discharge apertures 24 and 25 being separated by a transverse web 26 which forms a part of the bottom wall 21 of the guide structure 22 and from which an apron 45 depends for reasons to be given presently.

Extending along one longitudinal edge 27 of the bottom or auxiliary slide 23, and supported by the bottom wall 21 of the guide structure 22 (Figs. 5 to 10, inclusive) and in a plane substantially parallel to the bottom wall 21 of the guide structure 22 is a pressure or wedge bar 28 which is urged against the edge portion 27 of the lower or auxiliary slide 23 (bottom to top, Figs. 5 to 8, inclusive) by two springs 29, the pressure bar 28 being arranged in the guide structure 22 upon the bottom wall 21 of the guide structure 22 and between a side wall of the same and the edge 27 of the slide 23.

Formed in one longitudinal or side edge of the pressure bar 28 are two spaced indentations, cut-out portions, or recesses 31 and 32 (Figs. 5 to 8, inclusive), it being noted in Figs. 5 to 7, inclu-

sive, that an edge 41 of the pressure member 28 normally rests in engagement with the edge 27 of the slide 23.

Mounted on one side wall 46 of the guide structure 22 is a guide spring 47 (Fig. 11) which is adapted to engage one edge of the auxiliary slide 23 (bottom edge, Figs. 5 and 8) to guide the latter in its movement axially with the slide 14, for reasons to be given presently.

Formed in the guide 22 adjacent the side wall 46 of the latter are openings 48 and 49 which are in vertical alignment with respect to each other (Figs. 9 and 10). The wedge bar 28 is likewise provided with an opening 50 which is normally disposed eccentric of the aligned openings 48 and 49 of the guide 22 by action of the springs 29 upon the wedge bar 28.

A pin or peg 51 is adapted to be inserted into the aligned openings 48 and 49, and when the pin 51 is so disposed (Fig. 10) it is likewise passed through the opening 50 formed in the wedge bar 28, thereby bringing the opening 50 into vertical alignment with the openings 48 and 49 formed in the guide 22, whereupon the wedge bar 28 will be urged away from the edge 27 of the slide 23 against the action of the springs 29, thereby rendering the wedge bar 28 ineffective with respect to the auxiliary slide 23, the significance of which will become apparent presently.

Carried by the lower or auxiliary slide 23 and projecting upwardly therefrom is a stud or post 33 which projects upwardly into and through a slot 34 which is formed in the slide 14, the slide 14 including an angled portion 35 which is arranged at one end (Fig. 3).

Likewise carried by the lower slide 23 and depending therefrom is a stud or projection 36 (Fig. 4), and attached to this stud 36 is a resetting spring 37, this stud 36 projecting into the bottom discharge slot 25 and being adapted to work in an extension 39 of the same.

Operation

The tokens or checks used with the present token and coin separator are somewhat smaller in diameter than the coins used in connection with the same. Accordingly, when a token or check of the intended and proper diameter is placed in the coin aperture 19 of the slide 14 and the latter is pushed inwardly (left to right, Fig. 2), the token or check will drop from the coin aperture 19 of the coin slide 14 onto the depressed ledge 42 from which it will be dislodged by the depressed tooth 43 of the slide 14 into the sight opening or pocket 18 wherein it will be disposed upon the upper surface of the lower slide 23, it being understood that when the upper slide 14 is pushed inwardly (left to right, Figs. 2 and 3) the extension 35 engages the post or stud 33, whereupon the two slides 14 and 23 move together, thus moving the aperture 38 in the lower slide 23 out of registration with the sight opening or pocket 18, this movement of the two slides 14 and 23 being made against the action of the resetting spring 37 and the stud 36, during this operation, working in the slot 35-39.

Accordingly, when the parts are moved to full stroke position (as in Fig. 7) and released, the tensioned resetting spring 37 will return the slides 14 and 23 to their initial or coin-receiving positions (as in Fig. 2) thereby moving the coin aperture 38 in the lower slide 23 into registration with the sight opening or pocket 18, 75

whereupon the token which has previously been discharged into the sight opening or pocket 18, and is at this time resting upon the upper surface of the bottom slide 23, will now fall into 5 the coin aperture 38 of the bottom slide 23.

Accordingly, when the coin slides 14 and 23 are again moved inwardly, as above set forth, the token or check which is now disposed in the coin aperture 38 of the lower slide 23 will be 10 moved into registration with the token discharge aperture 24 whereupon it will be discharged through the substantially oval-shaped discharge aperture 24 (Figs. 2 and 4) and will be deflected by the depending apron 45 into the token storage magazine or receptacle 12, from which it 15 may be dispensed or ejected by means of the token or check dispensing apparatus with which the present coin separator is intended to be associated.

20 However, when a coin 53 of the intended and proper diameter is inserted into the coin aperture 19 of the coin slide 14 and the latter and the lower side 23 are pushed inwardly (left to right, Fig. 2), and are retracted into their initial or coin-receiving positions, by means of the tensioned resetting spring 37, the coin 53 which is at this time disposed in the sight opening 18, upon the upper surface of the lower slide 23, will fall into the coin aperture 38 of the bottom slide 23, and in this position a part of the peripheral edge portion of the coin will project through the opening 52 and into the notched or cut-out portion 31 of the pressure bar 28, whereupon, when the bottom slide 23 is again moved inwardly (left to right, Figs. 2, 4, 5, 6 and 7), the coin, being slightly larger in diameter than the tokens or checks which are used in connection with the device, will pass, along the upper surface of the bottom wall 21 of the guide structure 22, over the token-discharge aperture 24 and across the transverse web portion 26 of the bottom wall 21 of the guide structure 22, which web portion or partition 26 separates the coin discharge aperture 25 from the token discharge aperture 24. During this movement the peripheral edge portion of the coin, which is disposed in the coin aperture 38 of the lower slide 23, will ride out of the notched portion 31 of the pressure bar 28 and will bear against the edge 30 or wall 41 of the latter, thereby tensioning or compressing the springs 29 and thus causing the springs 29 to urge the pressure bar 28 into engagement with the coin which is disposed in the coin aperture 38 of the lower slide 23. This 35 pressure of the bar 28 against the coin which is disposed in the coin aperture 38 of the lower slide 23 will cause the said coin to remain in a horizontal plane, as it passes over the token-discharge aperture 24 and prevents the forward or advancing peripheral edge portion of the said coin from tilting or "nosing" downwardly as it passes over the coin discharge aperture 24, thus preventing the forward or advancing peripheral edge portion of the coin from engaging the transverse wall 26 which separates the token-discharge aperture 24 from the coin discharge aperture 25.

Accordingly, as the coin slides 14 and 23 are moved further inwardly (left to right, Figs. 2, 70 3, 4, 5, 6 and 7) the coin, which is at this time disposed in the coin aperture 38 of the bottom slide 23, will travel over the upper surface of the bottom wall 21 of the guide structure 22, and over the transverse web 26 which separates the 75 coin discharge aperture 25 from the token dis-

charge aperture 24 (Figs. 6 and 7), and will thus eventually be moved into registration with the coin discharge aperture 25, it being noted that during this movement of the coin moves progressively into the position in which the coin aperture 38 is shown in Fig. 7; and when the coin which is disposed in the coin aperture 38 of the bottom slide 23, comes into registration with the coin discharge aperture 25 that part of the peripheral edge portion of the coin which bears 5 against the edge or wall 41 of the pressure bar 28 will fall into the notched or recessed portion 32 of the pressure bar 28, thereby relieving the pressure of the coin upon the pressure bar 28 and the springs 29, whereupon the said coin 10 will fall through the coin discharge aperture 25 into a suitable receptacle which may be provided therefor in the cabinet of the apparatus 11 with which the present coin and token separator is 15 associated. 20

The coin slides 23 and 14 will then be reset into their initial or coin-receiving positions (as in Fig. 2) by the tensioned resetting spring 27.

In the practice of operating amusement devices 25 it is at times desired that all coins or tokens be discharged into one receptacle, which would under such circumstances require the removal of the token and coin separator of the type herein described and replacing the latter with a conventional coin chute. This, however, is overcome by 30 the present device by providing a pin or peg 51, having one end thereof terminating into a point which is inserted into the vertically aligned openings 48 and 49 of the guide 22 which will, as 35 has already been described, dispose the normally eccentric opening 50 of the pressure member 28 into vertical alignment with the openings 48 and 49 (Figs. 8 and 10) thereby urging the pressure members away from the auxiliary slide 23 against the action of the springs 29, whereupon the pressure member 28 will be ineffective in its function 40 with respect to the token and coin separator hereinbefore described. 45

With the device in the condition described in the foregoing paragraph, that is, with the pin 51 inserted through the openings 48, 49 and 50 (Figs. 8 and 10), the auxiliary slide 23 is guided in its movement axially with the slide 14 by the guide spring 46 which is mounted upon the side wall 45 of the guide 22 (Figs. 8 and 11). The coin chute 50 will now operate in a conventional manner, similar to the operation of the coin chute described in Patent No. 2,026,921, in this particular instance discharging both coins and tokens through the opening 24 formed in the bottom wall 21 of the 55 guide 22 whence they may be conveyed into a common receptacle by a chute, tube or any other conveyor (not shown).

While we have illustrated and described the preferred form of construction for carrying our 60 invention into effect, this is capable of variation and modification, without departing from the spirit of the invention. We, therefore, do not wish to be limited to the precise details of construction set forth, but desire to avail ourselves 65 of such variations and modifications as come within the scope of the appended claims.

Having thus described our invention, what we claim as new and desire to protect by Letters Patent is:

1. A coin and token separator comprising a 70 guide structure; a coin slide carried by the said guide structure and provided with a coin or token-receiving aperture; a second guide structure supported by and arranged below the said 75

- first-named guide structure and including a bottom wall provided with a token-discharge aperture and with a coin-discharge aperture, said discharge apertures being spaced from each other
5 in the direction of the axis of movement of said slides; a coin slide carried by the said second-named guide structure for movement by, and in a plane substantially parallel to and below, the said first-named slide, and said second-named
10 slide having a token or coin-receiving aperture formed therein with an open side wall opening into the edge of said slide and the same being adapted to receive a coin or token discharged from the said coin aperture of said first-named slide; means including a selector member co-acting with the said second-named slide to support a coin having a diameter slightly greater than that of a token of predetermined size in a plane substantially parallel to the plane of the said coin
15 apertures and of said second-named slide during movement of the said coin past the said token-discharge aperture and into the said coin discharge aperture, said second guide structure having a peg-receiving formation, and said selector member having a peg opening and being rendered ineffective in its aforesaid coin supporting operation by means of a peg inserted in the said peg-receiving formation in the guide structure and in the peg opening of the selector member.
20 2. A coin and token separator comprising a guide structure; a coin slide carried by the said guide structure and provided with a coin or token-receiving aperture; a second guide structure having a pin-receiving formation and supported by and arranged below the said first-named guide structure and including a bottom wall provided with a token-discharge aperture and with a coin-discharge aperture, said discharge apertures being spaced from each other
25 in the direction of movement of the slides and the said coin-discharge aperture being slightly wider than the width of said token-discharge aperture; a coin slide carried by the said second-named guide structure for movement by, and in a plane substantially parallel to and below, the said first-named slide, and said second-named slide having a token or coin-receiving aperture formed therein with an open side wall opening into the edge of the same said slide and adapted to receive
30 a coin or token discharged from the said coin aperture of said first-named slide; and means including a movable selector bar provided with a pin-receiving opening and co-acting with the said second-named slide to support a coin, having a diameter slightly greater than the width of the said token-discharge aperture, in a substantially horizontal plane in the said coin aperture of said second-named slide during movement of the said coin past the said token-discharge
35 aperture and into the said coin discharge aperture, said selector bar being rendered immovable to support a coin as aforesaid by means of a pin member inserted in the said pin-receiving opening thereof and in said pin-receiving formation of said second guide structure.
40 3. A coin and token separator including a guide structure having vertically aligned openings formed therein, and including a bottom wall provided with two spaced discharge apertures; a slide carried by the said guide structure for movement in a plane substantially normal to the common axis of the said aligned openings, means for moving said slide from a normal to a full-strike position, said slide having a token-receiving aperture with an open side wall part formed therein;
45

a pressure member arranged in said guide structure and normally bearing against an edge of said slide and having a notched edge part for registration with the open side of said token-receiving aperture in said slide when the slide is in initial position and further having an offset pin opening formed therein disposed out of register with the said vertically aligned openings in the guide structure when said pressure member is in normal effective position; said pressure member co-acting with the said slide to support a coin of a given or larger diameter in a substantially horizontal plane during the movement of the said slide from its said initial position to its full-stroke position so that the said coin may pass over the first one of said discharge apertures and into the other of the same in said guide, said pressure member having a second notched edge part for registration with the open side of the aperture in said slide when the latter is in full stroke position with its said token-receiving aperture registered with said second discharge aperture; and a pin adapted to be inserted through, and disposed in, the said vertically aligned openings and the said offset opening formed in the pressure member, the latter opening being registerable with the former by moving the said pressure member into ineffective position whereby the said pressure member will be held ineffective for movement against the said slide, thereby permitting coins and tokens to drop through the first one of said discharge apertures.
4. A coin and token separator for separating coins or tokens of different diameter comprising a guide structure; a slide carried by the said guide structure and provided with a token-receiving or coin-receiving aperture; a second guide structure arranged below the said first-named guide structure and including a bottom wall provided with two spaced discharge apertures; a slide carried by the said second-named guide structure for movement in a plane substantially parallel to but below the said first-named slide and by the latter, said second-named slide having a master token-receiving or coin-receiving aperture with an open side formed therein and adapted to receive a coin or token discharged from the said coin aperture of said first-named slide; a yieldable pressure member arranged in the second-named guide structure and having a notched edge registered with the open side of said master aperture when the slide of the latter is in initial position co-acting with the said second-named slide to firmly support a coin of a determined diameter substantially in the plane of the said master coin aperture and the said second-named slide during the movement of the latter from its normal or initial position into its effective or full-stroke position by said first slide, so that a said coin may pass over the first one of said discharge apertures and into the other of the same while a token of lesser diameter than said coin will drop through said first one of said discharge apertures, the said notched part of said pressure member engaging an edge part of a coin or token of a determined or larger diameter which edge part protrudes through the said open side of the master aperture, while coins or tokens of less than said determined diameter are not engaged by the notched part of said pressure member and are not carried over said first one of said discharge apertures; and means for rendering the said pressure member inactive relative to the said second named slide thereby causing the said coin to drop through the first one of
50
55
60
65
70
75

- said discharge apertures, said means including a peg member insertible into a peg aperture provided in said guide member and a second peg aperture in said yieldable pressure member and 5 normally out of register with said first peg aperture when the pressure member is in effective position, the said peg apertures being alignable for reception of said peg by moving said pressure member out of effective position.
- 10 5. A coin and token separator comprising a guide structure; a coin slide carried by the said guide structure and provided with a receiving aperture for coins or tokens; a second guide structure having a pin opening and supported by and 15 arranged below the said first-named guide structure and including a bottom wall provided with a token-discharge aperture and with a coin-discharge aperture, said discharge apertures being spaced from each other; a coin slide carried by 20 the said second-named guide structure having means for operative engagement by said first slide for movement in a plane substantially parallel to but below the said first-named slide; said second-named slide having a token or coin-receiving aperture formed therein disposed to receive a 25 coin or token after the discharge of the same from the said coin aperture of said first-named slide and adapted to expose an edge portion of a said coin or token for engagement with coin 30 supporting means; means cooperating with the said second-named slide to support a coin, hav- ing a diameter slightly greater than that of a token of predetermined size and which will drop through said token discharge aperture, in a substantially horizontal plane in the said coin aperture of said second-named slide so that the said 5 coin may be moved uniformly past the said token discharge aperture and into the said coin discharge aperture; said means comprising a pressure bar carried by the said second-named guide structure and including a pin-receiving formation and an edge portion having a pair of spaced notches or indentations formed therein; the said coin aperture of the said second-named slide being further disposed to expose a said coin or token edge in registration with one of said 15 notches when the said second-named slide is in its normal or initial position; and the said coin discharge aperture being disposed in registration with the other of said notches; urging means carried by the said second-named guide structure 20 for urging the said edge portion of said pressure bar into engagement with said second-named slide; and means including a pin receivable in the said pin opening of said second guide structure and in the pin-receiving formation in said pressure member to hold the latter out of effective position relative to said second-named slide 25 against the action of said urging means.
